UNITED STATES PATENT OFFICE.

SCOTT HORNER, OF ST. LOUIS, MISSOURI.

LINING FOR SEWERS AND THE LIKE.

1,050,137.

Specification of Letters Patent. Patented Jan. 14, 1913.

Application filed September 20, 1909. Serial No. 518,684.

To all whom it may concern:

Be it known that I, SCOTT HORNER, a citizen of the United States, residing at St. Louis, Missouri, have invented a certain new and useful Improvement in Linings for Sewers and the Like, of which the following is a full, clear, and exact description, such as will enable others skilled in the art to which it appertains to make and use the same, reference being had to the accompanying drawings, forming part of this specification, in which—

Figure 1 is an end elevation of a sewer or conduit, the same being provided with lining constructed in accordance with my invention. Fig. 2 is a perspective view of one of the sections of my improved lining.

My invention relates to a lining for sewers, conduits and the like, the principal object of my invention being to construct a lining which is made up of a series of interlocking blocks or sections, the same being formed of vitrified earthen material or the like, thus providing a smooth hard surface for the interior of the sewer or conduit, the outer portion of which is constructed of hardened plastic material anchored in grooves formed in the outer faces of the lining blocks or sections.

To the above purposes, my invention consists in features of novelty hereinafter more fully described and claimed.

Referring by numerals to the accompanying drawings, 1 designates the body of one of the blocks or sections, the same being preferably formed of vitrified earthen material and of any convenient length and thickness, and said block is segmental in cross-section, its curvature corresponding to the size of the sewer or conduit to be formed. The inner face 2 of the block is perfectly plain and smooth, and formed in one of the side edges of each block is a longitudinally extending groove 3, which is adapted to receive a corresponding rib 4 formed on the opposite edge of the next adjacent block or section. Thus when a number of the blocks or sections are assembled in circular arrangement to form the lining of the sewer or conduit, the rib 4 on each block interlocks in the groove 3 of the next adjacent block, thus maintaining all of the blocks in proper position while the self-hardening plastic material is applied to the exterior of the lining.

Formed in the outer face of each block is

one or more longitudinally extending grooves 5, which are preferably dovetailed in cross-section, and formed in this outer surface of the block and intersecting the grooves 5 is one or more transversely disposed grooves 6, the same being dovetailed in cross-section. These intersecting dovetailed grooves 5 and 6 provide means in the form of a medial series of under-cut projections on the convex surface of the tile and two marginal series of under-cut projections which follow respectively the edges of the tile, which projections have their outer faces flush with the sides of the tile, all of which projections providing a means whereby the body of concrete 7, or analogous self-hardening plastic material, is firmly anchored to the interior of the blocks forming the lining, and after the body of concrete or the like has been applied to the lining a very strong, durable and permanent sewer or conduit is formed. The marginal series of projections on the convex surface of the tiles are formed with relation such to the marginal grooves and tongues that when the tiles are laid together with their tongues and grooves interlocking the outer faces of the marginal projections contact. In this manner there is provided along the edges of each tile a means whereby the tiles are held firmly in the plastic material at their sides and held in close contact with one another along their contiguous edges.

By utilizing blocks of vitrified earthen material, a very strong, smooth lining is provided for the sewer or conduit, and as said blocks are impervious to water, the sewer or conduit lined with said blocks will not tend to wear away or leak, as is the case where sewers or conduits are composed wholly of concrete or the like.

I claim:

As an article of manufacture, a tile for lining a conduit comprising a body segmental in cross section and having medially on its convex side a longitudinal series of under-cut projections and having along each lateral edge a longitudinal series of projections under-cut on their three inner sides and having their outer faces flush with the sides of the tile, said tile being further provided on one of its lateral sides with a longitudinal tongue formed adjacent to the series of openings adjacent said side, and being provided with a longitudinal groove formed in the opposite side below the series

of projections adjacent said side, said groove and said tongue being adapted to register with similar tongues and grooves on juxtaposed tiles, and said lateral projections acting to hold said registering tongues and grooves in contact by the pressure of material surrounding said projections.

In testimony whereof I hereunto affix my signature in the presence of two witnesses, this 18th day of September, 1909.

SCOTT HORNER.
